LUBRICATED REFRIGERANT COMPRESSOR

Jens Touborg, Tecumseh, Mich.

Application March 30, 1940, Serial No. 327,063

2 Claims. (Cl. 230—206)

This invention relates to compressors, and it has particular reference to the provision of improved means for automatically supplying limited quantities of lubricant to the head end of the piston and cylinder assembly, during operation of the apparatus.

While the present invention is generally applicable to compressors, it will herein be described with particular reference to a hermetic compressor employed in an artificial refrigeration system. In the well-known compressor-condenser-expander type of refrigerating machine, the refrigerant vapor is compressed, delivered to the condenser where the hot vapors are cooled, and then to the expansion coil wherein the refrigerant volatilizes with absorption of heat. The expanded vapors are then returned to the compressor for compression, to repeat the cycle. More or less oil is picked up by the refrigerant during its passage through the compressor, and is carried into the remaining parts of the system where it tends to remain, thus decreasing the efficiency of operation. Accordingly, one objective in designing refrigeration compressors and systems has been to provide means for minimizing this oil circulation, and, generally speaking, it may be said that, at this date, the problem of keeping an excess of oil out of the condenser and expander has been reasonably well solved.

Insofar as the necessary function of supplying lubricant to the moving parts of the compressor itself is concerned, it may also be noted that the art has been inclined to deem this problem no longer of serious consequence. Thus, by immersing the parts, or some of them, in an oil bath, by providing oil ducts and the like between suitable points, the art has assumed that a sufficient supply of oil is made available.

However, as I now find, these diametrically opposed desiderata—namely, keeping the oil out of the compressed refrigerant, but getting adequate oil to all working parts—have not been both entirely satisfied, and the primary purpose of this invention is to provide means whereby both purposes are effectively achieved.

By way of preliminary explanation of the underlying principle of this invention, as I now understand the same, it may be noted that a compressor, operating in an entirely satisfactory manner under normal loads, will suddenly develop a "knock" or noise in the presence of high or abnormal head pressures. Examination of returning refrigerant, as by passing it through a sight-glass, will show a reasonable freedom from excess amounts of oil, while examination of the

lubricating ducts and the like will show that they are free and open, so that plenty of oil ought to flow to all the working parts. The noise, however, will continue as long as the head pressures remain high, and as such noises are frequently indicative of faulty lubrication, the question presented is as to the cause of the noise.

I find that such noises or knocks result from the pressure effect of the refrigerant on the oil film between the piston and cylinder wall, wherein the oil is actually blown back into its several passages by the pressure of the abnormally compressed refrigerant, with the result that the head end, and the valves, are operating in a substantially dry, or unlubricated condition. Upon attempting to correct this difficulty by making the oil passages larger, one of two undesirable results obtain. First, there may be so much oil admitted as to saturate the discharged refrigerant during normal operation, which, as noted above, is not desirable. Second, the head pressure, if sufficiently high, continues to block lubrication of the terminal portions of the piston, and thus nothing is accomplished.

In order to eliminate this defect of dry head ends, and at the same time prevent the admixture of undue amounts of oil with the compressed refrigerant, I now propose to design the head end of the compressor in such manner that the vapor pressure itself becomes the means of automatically forcing adequate quantities of lubricant into the head end of the cylinder whenever head pressures rise above a predetermined normal.

The invention will be more clearly understood from the following detailed description of a specific embodiment thereof, illustrated in the accompanying drawing, wherein:

Fig. 1 is a section of a hermetic compressor of a type utilized in refrigeration service; and,

Fig. 2 is an enlarged fragmentary section of the head end of the compressor, showing the novel oil passages in greater detail.

For illustrative purposes, the invention is shown organized with a refrigerant compressor unit of the hermetic type, wherein an integrated two-part casing 10, 11 encloses a compressor mechanism 12 and the motor 13 for driving the same. The frame for the compressor mechanism 12 consists of a single casting 15 having a crank-case portion 16, a cylinder block portion 17, and an enlarged upstanding circular flange 18. The casting is assembled with the casing by pressing the flange 18 into the upper part 10 of the casing. The stator 19 of the motor 13 is pressed into the interior of the flange 18.

The crankcase portion 16 is formed with a vertical bearing 21 for rotatably receiving a crankshaft 20 which projects therethrough and is affixed to the overlying rotor 13a of the motor 13. The lower end of the crankshaft 20 is carried in a bearing block 23, which block is secured to an annular shoulder 24 on the portion 16.

The cylinder block portion 17 is bored to form a horizontal cylinder 25, and the cylinder is capped by a head 26 and an interposed valve plate 28. A piston 30 is mounted in the cylinder 25, and it carries a wrist pin 31 to which is fitted the small end bearing 32 of a connecting rod 33. The other end of the rod 33 is formed with a bearing strap portion 34 which is disposed about an eccentric portion 20a of the crankshaft 20.

Lubricating oil is preferably conveyed to the various bearing surfaces under pressure by any suitable pumping means known in the art. In the present instance, a centrifugal pump is formed within the crankshaft 20 by drilling an off-center longitudinal passage 35 and communicating radial passages 36, 37, and 38 therein. The bottom of the crankshaft is formed with an axial passage 41 which communicates with the passage 36, and thus provides the eye portion of a centrifugal pump. An underlying thrust plate 40, secured to the block 23, is drilled to permit the passage 41 to receive oil from the surrounding oil body. Thus, the oil is forced up the passage 35 and out of the axial passages to lubricate the crankshaft bearing 21 and bearing block 23, and also the eccentric strap 34. The connecting rod 33 is drilled through the strap 34, as indicated by the numeral 40, so that oil is also supplied to the wrist pin 31. The wrist pin 31 (Fig. 2) contains an axial passage 45, through which oil is deposited on the wall of the cylinder 25.

The piston 30 is formed with oil grooves 47, 48 and 49, and a terminal pick-up groove 50, the latter groove clearing the cylinder at the bottom of the piston stroke, so that it may receive splashed lubricant from the crankcase and deposit it later on the cylinder wall. It will thus be seen that as the piston is reciprocated, the oil supplied by the groove 50 and through the wrist pin 31, is spread over the surface of the cylinder wall to be later picked up by the oil groove, so that all but the end of the cylinder is amply provided with lubricant. The cylinder wall is formed with a partial groove or pocket 51, which serves as a reservoir for the piston grooves.

Thus, as the piston reciprocates, a certain amount of oil picked up in the terminal groove 50 is wiped over the surface of the cylinder bore, while another amount of oil flows through the wrist pin passage 45, and is partially admitted to the groove 49. As the piston advances toward the head end, the passage 45 is momentarily aligned with the reservoir 51, and oil is then discharged directly therefrom into the reservoir to keep it filled. Oil in the duct 45 is, of course, under pressure developed in the lubricating pump 36. As the grooves 47 and 48 pass the reservoir, for example, on the next stroke, they are replenished therefrom with oil, which is thus made available for lubricating the portions of the cylinder wall which they traverse, and for supplying oil to the hereinafter described port 65, to the extent that the head pressure indicates.

Refrigerant from the evaporative portions of the refrigeration system (not shown) is directed into the casing portion 18 through a fitting 52, and thence it is drawn into a suction pipe 53

leading downward to the cylinder block portion 17 of the frame casting 15. The block portion 17 is formed with an inlet passage 54 communicating with the pipe 53, and also with a hole 55 in the valve plate 28, which hole leads to an inlet chamber 56 in the head 26. In effect, the inlet passage 54 and hole 55 may be considered part of the inlet chamber 56. The inlet chamber 56 communicates with the cylinder bore through a port 56a in the plate 28, which port is closed by a leaf spring valve 57. The plate is also formed with an outlet port 58, which is closed by a spring-pressed valve 60. Thus, on the suction stroke of the piston, gaseous refrigerant is drawn into the cylinder bore 25 through the port 56a and, on the return stroke, the refrigerant is expelled under compression through the port 58 into an outlet chamber 61, whence it is directed out of the unit through a drilled passage 62 and a communicating pipe 63.

It will be observed that the inlet passage 54 and the cylinder bore 25 are connected by a small vent port 65, which port is so disposed as to be always covered by the piston 30. During operation of the compressor under normal loads, it will be apparent that the close running fit of the piston in the cylinder, plus the oil film therebetween, will be sufficient to prevent gas leakage or "blow-by," and accordingly the port 65 will remain functionally inoperative. When severe head pressures are encountered, however, the gas on the compression stroke of the piston will tend to displace the oil film between the piston and cylinder wall. In a well fitted piston, such penetration would probably not extend farther than the second oil groove 48. This breakdown of the oil film causes what is known as "dry knock" and it is a signal, in prior structures, that the upper portions of the cylinder wall are being temporarily deprived of proper lubrication.

In the present invention the provision of the oil duct 65 provides an escape for the oil directly into the inlet passage 54 whenever head pressures are sufficiently high as to cause gas penetration of the piston areas, as above outlined. In this event, it will be obvious that the gas pressure will force the oil contained in the grooves 47 and 48 out of the port 65 and into the inlet passage 54. This occurs during the compression stroke of the piston when such grooves pass the port 65. On the subsequent suction stroke of the piston, it will be seen that the small quantity of oil thus deposited in the inlet passage 54 will be drawn into the cylinder with the incoming charge, thus being deposited on the walls of the cylinder and providing adequate lubrication for this portion of the cylinder upon the next passage of the piston.

When normal conditions in the system are gradually restored, and head pressures become correspondingly lower, the quantity of oil which escapes through the port 65 will become smaller in volume, until the oil carried by the piston is sufficient for complete lubrication of the cylinder wall. Thus, the port arrangement provides for automatic metering of oil to the upper areas of the cylinder in response to pressure variations in the system.

It is not intended that the invention be limited to the type and style of compressor herein illustrated, since it will be obvious to those skilled in the art that the principle set forth may be incorporated, with slight modifications, in all types of compressors.

I claim:

1. In a compressor having a reciprocable piston mounted in a cylinder bore having a head end, and inlet and outlet chambers communicating with the cylinder bore, oil supply means for the head end cylinder portions responsive to pressure conditions in the outlet chamber, comprising a port extending into the cylinder bore and connecting the bore with the inlet chamber, said port being so located as to be covered by the piston during all phases of reciprocation thereof, oil grooves in the piston registering with the port during movement of the piston, and means for supplying oil to the grooves, whereby oil supplied to said grooves is periodically transmitted to the port and thence to the head end of the cylinder bore in response to said pressure conditions.

2. In a compressor having a reciprocable piston

mounted in a cylinder bore having a head end and inlet and outlet chambers communicating with the cylinder bore, said inlet chamber having an extended passage portion disposed adjacent to the cylinder bore, oil supply means for the head end cylinder portions responsive to pressure conditions in the outlet chamber, comprising a port connecting the cylinder bore with said extended passage, said port being so located as to be covered by the piston during all phases of reciprocation thereof, oil grooves in the piston registerable with the port during movement of the piston, and means for supplying oil to the grooves, whereby oil supplied to said grooves is periodically transmitted to the port and thence to the head end of the cylinder bore in response to said pressure conditions.

JENS TOUBORG.
